HOLDER FOR COINS AND KEYS

Jerome Lippman, 275 N. Portage Path, Akron, Ohio

Filed May 17, 1965, Ser. No. 85,322

Term of patent 14 years

(Cl. D87—3)

FIG. 1

FIG. 2

FIG. 4

FIG. 3

FIGURE 1 is partially broken away for convenience of illustrating coins and a key, depicted by means of broken lines, for illustrative purposes only, in the holder.

I claim:

The ornamental design for a holder for coins and keys, as shown and described.
